Atty's.

UNITED STATES PATENT OFFICE.

ERNEST WOOLER, OF CLEVELAND, OHIO, ASSIGNOR TO CLEVELAND AUTOMOBILE COMPANY, OF CLEVELAND, OHIO, A CORPORATION OF DELAWARE.

DESIGN FOR A WINDOW, NAME-PLATE, OR ARTICLE OF SIMILAR NATURE.

56,905.

Specification for Design.

Patented Jan. 4, 1921.

Application filed July 11, 1919. Serial No. 310,281. Term of patent 14 years.

To all whom it may concern:

Be it known that I, ERNEST WOOLER, a citizen of Great Britain, residing at Cleveland, county of Cuyahoga, and State of Ohio, have invented a new, original, and ornamental Design for Windows, Name-Plates, or Articles of Similar Nature, for Motor-Vehicles, of which the following is a specification, reference being had to the accompanying drawing, forming part thereof.

The figure is a plan view of a window showing my new design..

I claim:

The ornamental design for a window, name plate, or article of similar nature as shown.

ERNEST WOOLER.
